United States Patent Office

Des. 186,602
Patented Nov. 10, 1959

186,602

WALL TELEPHONE COIN BOX

Benjamin W. Friedman, Bridgeport, Conn.

Application October 16, 1958, Serial No. 53,006

Term of patent 14 years

(Cl. D26—14)

Fig. 1

Fig. 2

Fig. 3

Figure 1 is a front elevational view of a wall telephone coin box showing by new design;

Fig. 2 is a side elevational view, the opposite side being substantially a mirror image thereof;

Fig. 3 is a rear elevational view; and

Fig. 4 is a top plan view thereof.

I claim:

The ornamental design for a wall telephone coin box, as shown, and described.
